United States Patent Office

Des. 196,756
Patented Oct. 29, 1963

196,756

MICROFILMING MACHINE

John Ray Regal, Elizabeth, N.J., assignor to Sperry Rand Corporation, New York, N.Y., a corporation of Delaware

Filed Dec. 20, 1962, Ser. No. 72,907

Term of patent 14 years

(Cl. D61—1)

FIG. 1

FIG. 2

FIG. 1 is a front perspective view of a microfilming machine embodying my new design; and

FIG. 2 is a rear perspective view thereof.

The essential features of the design reside in the portions shown in solid lines.

I claim:

The ornamental design for a microfilming machine, substantially as shown and described.
